UNITED STATES PATENT OFFICE.

WILLIAM LEE HANLEY, JR., OF BRADFORD, PENNSYLVANIA.

TUNNEL KILN.

Application filed January 9, 1923. Serial No. 611,597.

To all whom it may concern:

Be it known that I, WILLIAM L. HANLEY, Jr., a citizen of the United States, residing at Bradford, in the county of McKean 5 and State of Pennsylvania, have invented certain new and useful Improvements in Tunnel Kilns; and I do hereby declare the following to be a full, clear, and exact description of the invention, such as will enable others skilled in the art to which it 10 pertains to make and use the same.

My invention consists in the novel features hereinafter described, reference being had to the accompanying drawings which 15 show one form of tunnel kiln embodying my invention, selected by me for purposes of illustration, and the said invention is fully disclosed in the following description and claims.

20 My invention relates to tunnel ovens designed more particularly for firing coarse clay products such as bricks, fire brick, tile, etc., in the operation of which three items are of greatest importance, to wit, low cost 25 of plant, low cost of operation, and large output. In tunnel kilns for this purpose it is desirable that the goods treated should after the usual preliminary drying, be passed from a cooler or preheating zone to 30 a hotter or fire zone, and thence to a cooler zone, for cooling the fired products. It has been proposed in the construction of tunnel kilns to employ combustion or heating chambers extending longitudinally through the 35 tunnel kiln or oven, within which combustion takes place adjacent to the zone of highest temperature, the heated products of combustion being conducted within said chambers through the cooler preliminary heating 40 zone or zones without coming into contact with the goods under treatment. While this type of kiln or oven is commercially practical and efficient in the manufacture of 45 many articles, it is open to a number of objections in connection with the firing of coarse clay products, which have to a very large extent operated to prevent extension of the use of kilns or ovens of this type to such products. Among these objections may 50 be mentioned the following. The extremely high initial cost of the oven plant, which is due to a number of factors including the expensive structure of the separate heating chambers of the best fire resisting material 55 to withstand the high heat in the hotter zones;

the necessity of using gaseous fuel which in most installations would require the building and operation of a gas producing plant, at high initial cost, and followed by high operating cost and necessitating a high degree of skill in its operation to secure efficient operation; the high cost of upkeep of the kiln itself due to the breaking down and disintegration of the combustion chambers within the firing zone of the oven, and the slowing down of output due to necessary 60 repairs and replacements, which necessitate stopping the operation of the kiln and cooling it to enable workmen to enter the firing zone.

As a result of extended observation and experience as a practical manufacturer of brick, tile, etc., which I term "coarse clay products" to distinguish them from the finer grades of clay products such as porcelain, pottery, etc. I have invented a novel tunnel kiln which, while it may be useful for other purposes, is especially designed for firing brick, tile and other coarse clay products, the actual firing in the zone of highest heat being accomplished by direct firing, permitting the use of whatever fuel may be the cheapest at the location of the plant, whether coal, wood, gas, oil, etc., and permitting of a much cheaper construction of that portion of the firing zone. The products of combustion are then led within longitudinal flues through the preheating zones, and as the gases of combustion have already parted with much of their heat in the firing zone, and are at considerably lower temperature where they enter the flue systems, the flues can not only be constructed of comparatively cheap material, but such flues are not subject to any such deterioration as is the case where they extend through the zone of highest heat and therefore the flues will last for years with little or no repairs and little or no interruption of operation, which thus results in maximum output.

It is possible to use direct firing in treating coarse clay products as they are not injured by direct contact with the products of combustion. The bricks or tile to be fired are piled or loaded upon cars which are moved longitudinally through the kiln or oven, and when subjected to the greatest heat by contact with the products of combustion from direct firing, there is a slight shrinkage of the mass.

- It is extremely important that the firing should be uniform throughout the piles or stacks on the cars, as an unequal distribution of heat would result in firing portions of the bricks while other portions might be left in unfired condition. The unequal distribution of heat would also cause the bricks to shrink locally in the piles at points where exposed to the greatest heat, thus causing the superimposed rows of brick to tilt with likelihood of causing the bricks to come into contact with the walls of the oven or kiln, or to topple off of the cars producing a "wreck" within the kiln, which would require the withdrawal of all the cars and a suspension of operation until the entire kiln had cooled, so that it could be repaired, or the wrecked car or cars removed and the rails cleared.
- According to my invention the kiln or oven is specially constructed so that the products of combustion from the direct firing furnaces are caused to enter the kiln near the bottom of the heating chamber, and are conducted to the top of the chamber through lateral passages between the oven wall and longitudinally disposed flues interposed between the said passages and the goods, and are discharged toward or at the top of the oven preferably from both sides, where they are deflected downwardly into and through the goods on the cars, which are arranged so as to leave a central vertical passage for the purpose. The hot products of combustion therefore enter each carload of bricks in the center and are distributed laterally and uniformly toward the lateral edges so that there is no danger of too rapid shrinkage of the outer rows of bricks which would topple them off of the car, or into contact with the laterally arranged parts of the tunnel structure. The lateral flues are provided with special means hereinafter more fully described for preventing the heated gases entering the oven from passing downwardly between the goods and the lateral flues, and consisting in tapering upwardly and inwardly extending portions on said flues, and a lateral rib or ribs on the inner face thereof. The central portion of the roof of the oven in the hot zone is also preferably provided with a downwardly extending longitudinal tapering rib having curved lateral faces which coacts with the other features of the oven in directing the entering hot gases downwardly into the goods. The lateral flues in the firing zone are provided with inlet apertures adjacent to the bottom of the firing chamber to receive the products of combustion after they have acted on the goods directly, and convey the products of combustion through the heating flues of the preheating zone or zones of the kiln toward the forward end at which the cars are introduced, where the products of combustion are withdrawn by means of a fan or stack. This permits the products of combustion to effect the graduated preheating of the goods in the preheating zone or zones, the heat being transmitted to the air in the oven drawn in at the front end of the same, by means of a suitable fan and distributed to the direct firing furnaces, thus supplying heated air for the combustion of the fuel therein. I also prefer to provide means for drawing cooling air from the discharge end of the kiln or oven through a cooling flue conveniently located in the roof portion of the cooling zone thereof, which air is gradually heated up by the heat extracted from the goods as they are slowly cooled, and the heated air may be conveniently discharged into a separate drying chamber and utilized in driving the moisture out of green bricks or tile previous to passing them through the kiln or oven.
- By improved construction the unequal heating of the bricks on the cars, and particularly the burning of the bricks at the lateral portions of the piles of brick on the cars, which would result in toppling them over against the oven structure, is prevented, as the lateral flues in the firing zone prevent the products of combustion from directly impinging upon the lateral portions of the piles of brick on the cars, and the construction and arrangement of the firing zone substantially prevents the products of combustion from descending through the space between the piles of bricks and the adjacent inner lateral walls of the lateral flues in the firing zone, and forces the products of combustion to enter the piles of bricks from the top and centrally thereof, so that should any premature settling of any portion of the piles of brick result, it will take place in the longitudinal center thereof, and merely tend to tilt the bricks toward the center and not outwardly, thus preserving the integrity of the piles and avoiding accidents which otherwise would interfere with the efficiency of the kiln.
- Referring to the accompanying drawings, Figs. 1 and 1^a represent a plan view, partly in section, of a tunnel kiln constructed in accordance with and embodying my invention, portions being broken away.
- Fig. 2 represents a vertical transverse section on the line 2—2 of Fig. 1, taken through the firing zone of the kiln.
- Fig. 3 is a partial transverse sectional view taken on the line 3—3 of Fig. 1, through one of the preheating zones of the kiln.
- Fig. 4 is a similar partial transverse sectional view taken on the line 4—4 of Fig. 1, through another of the preheating zones of the kiln adjacent to the end at which the goods are introduced.
- Referring to the embodiment of my in-

vention illustrated in the drawings, it will be understood that these drawings are more or less diagrammatic necessarily on account of the reduced scale on which they are drawn. This kiln, which represents the preferred form of my invention, comprises a central section, indicated at A, which I term the firing section, in which the greatest heat is maintained, a preheating section, indicated at B, and extending from the firing section to the forward end of the kiln at which the goods are introduced, and a cooling section, indicated at C, extending from the firing section, A, in the opposite direction, within which the fired bricks or other coarse clay products are cooled before being discharged from the kiln. It will be understood that the central portion of the entire kiln is provided with a longitudinal goods space sufficiently wide to admit the passage through the kiln of a succession of cars or trucks upon which the goods to be fired are loaded, the lower portion of the goods space being provided with suitable rails to support the cars or trucks and permit their being advanced gradually or intermittently from the front end of the kiln to the rear end as the operation proceeds.

Referring to Fig. 2, which illustrates a transverse vertical section through the firing section or firing zone, of the kiln, 1-1, represents the side walls of the kiln, and 2, the roof portion thereof, which is in the form of a curve or arch, and is preferably provided with a central longitudinally extending, rib, 3, projecting downwardly from the roof and provided on opposite sides with curved deflecting surfaces, indicated at 4-4, extending from the adjacent inner faces of the roof to the lower end of the rib, 3. The walls and roof are formed of any suitable fire resisting material and the side walls are preferably reinforced by vertical standards, 5, connected by cross ties, 6, in a well known manner. Along opposite sides of the firing section, I provide a plurality of direct firing furnaces, indicated at 7, having suitable grates, 8, and provided with suitable means for the admission of fuel and the supplying of necessary air for combustion. These furnaces are indicated more or less diagrammatically in Figs. 1, 1^a and 2. Within the kiln structure and on opposite sides of the central goods space, longitudinal platforms, 9, are arranged between the back wall, 10, of the adjacent furnaces, and the central space occupied by the trucks or cars, these platforms preferably being provided as usual with overhanging ledges or ribs, 11, at the upper part of their inner faces to project over a portion of the truck or car structure, and prevent the extremely hot products of combustion from coming in contact with the frames and wheels of the cars or trucks. Upon these platforms, 9,

within the firing section of the kiln, and on opposite sides of the central goods space, I erect receiving flues, indicated at 12-12, the walls, 13, of which are supported on the platforms, 9, adjacent to the rear walls, 10, of the furnaces, the upper portion of the flue structure being curved, as indicated at 14, so as to follow generally the curvature of the roof, 2, of the kiln, and at the extreme upper end of each of these flues is an inwardly and upwardly extending longitudinal guard flange, indicated at 15, the upper or outer face, 16, of which forms a continuation of the curved upper face, 14, while the inner face, 17, is preferably given a curve from the projecting end of the guard flange, 15, to the upper portion of the vertical inner face, 18, of the flue. It will be seen that the space between the upper face, 14, of these flues and the contiguous portions of the roof portion, 2, forms a passage, 20, for conducting the products of combustion from the furnaces, 7, upwardly and inwardly toward the topmost portion of the kiln where they are deflected downwardly by the central rib, 3, upon the top and central portions of the goods loaded upon the cars or trucks within the firing section. It is necessary to allow sufficient space between the outer surfaces of the piles of brick on the cars and inner faces of the flues, 12, so that there shall be no danger of the bricks or other goods coming in contact with the flue walls, 18, especially adjacent to the top where such an accident is most likely to occur, and it is particularly desirable to prevent a down draft of the heated products of combustion into these lateral spaces adjacent to the flue walls, 18, and the lateral faces of the piles of goods on the cars, which would have the result of completing the firing and consequent shrinkage of the bricks or tiles at the outer edges of the piles, and thereby cause the piles to topple outwardly, with consequent danger of a wreck within the kiln. The object of the longitudinal guard flanges, 15, at the top of the receiving flues, 12, is to guide the products of combustion over to the central portion of the kiln and prevent them from being carried downward from the discharge passages, 20, into the spaces between the inner faces of the receiving flues and the goods. To further and more efficiently prevent this down draught of the products of combustion laterally of the goods, I prefer to provide the inner vertical wall, 18, of each of the receiving flues, with one or more inwardly projecting longitudinally extending ribs or baffles, which are preferably located at different points vertically along the walls, 18, and are preferably of different horizontal widths, that is to say, the lower ribs, 19, extend inwardly a greater distance than the upper ribs, 19, as there is less lat-

eral movement of the brick piles on the cars adjacent to the lower portions thereof, than at the top, and consequently less danger of the piles of goods coming into contact with such ribs. The inner walls, 18, of the receiving flues are provided at their lower ends adjacent to the platforms, 9, with inlet apertures, 21, so that the products of combustion which descend vertically through the goods 10 and permeate laterally therefrom toward the outer faces of the piles, may be drawn into the interior of the receiving flues through the inlet apertures, 21. The construction of the receiving flues requires no special forms 15 or materials, but they may be built permanently of fire brick or other suitable material in accordance with the usual practice in building flues subjected to high temperatures, and these flues can be cheaply constructed 20 and will give efficient service with a minimum of expense for repair and reconstruction.

Forward of the firing section, A, of the kiln, is located the preheating section, B, throughout which the side walls and roof 25 portion of the tunnel are constructed substantially as hereinbefore described, except that the longitudinal rib, 3, in the roof, 2, may be omitted, as indicated in Figs. 3 and 4, although it may also be carried through the 30 preheating section, B, as in the firing section Fig. 2, if desired. In the preheating section, B, the platforms, 9—9, with their overhanging ledges 11 are continued so as to afford protection for the frame and wheels of the 35 trucks or cars, but throughout the preheating section, I prefer to employ a different type of flue or flues to receive the products of combustion from the receiving flues, 12—12. The preheating section, B, may also 40 be advantageously subdivided into zones of varying temperature, the temperature decreasing from the firing section toward the forward end of the preheating section. In the present instance I have shown the preheating section, B, as comprising two zones, 45 indicated at B' and B'', and I have shown in Fig. 3 a type of heating flue therefor which I prefer to employ in the zone, B'', while in Fig. 4 I have illustrated a type of 50 heating flues which may be conveniently employed in the zone, B', where the lowest temperature in the kiln exists, the desideratum being to employ flues having the highest efficiency for heating the air in the preheating 55 section, while being at the same time constructed of materials capable of withstanding the temperature of the products of combustion passing therethrough.

Thus, in Fig. 4, I have shown the tunnel 60 provided with heating flues erected upon the platforms, 9, of the well known Dressler type, such as are illustrated, for example, in United States Patent to Dressler, No. 1,330,432, except that the inner walls of the 65 sections forming the flue construction are im-

pervious adjacent to the pile of bricks, as indicated in Fig. 3. Briefly stated, the flue construction which is independent of the kiln itself, and is supported on the platform, 9, thereof, is provided with a central flue, 30, 70 formed between surrounding hollow walls, 31, indicating the bottom wall, 32, the inner wall, 33, the exterior wall, and 34, the inclined top wall, all of which are hollow and communicate with each 75 other for the purpose of providing for a circulation of air within the hollow walls, and discharging the same into the interior of the kiln chamber, for the purpose of the preheating of the bricks or tiles, etc., on the 80 cars or trucks. It will be understood that the flues, 30, communicate with and receive the products of combustion from the receiving flue, 12, of the firing section of the kiln. It is to be understood, however, that by the 85 time the products of combustion enter the heating flues, 30, they have parted with a very considerable portion of their heat in the firing chamber, so that at the time they enter the heating flues, 30, their temperature 90 is so far reduced, that they will not cause material deterioration of the hollow walls of the heating flues, even after their extended use. Consequently the heating flues will last indefinitely without likely repair or 95 reconstruction which would not be the case were the heating flues themselves employed for the actual combustion of the fuel, as is usually the case where this type of flue is employed.

In the preheating zone, B', a considerably lower temperature will be maintained than in the zone, B'', and I therefore find it advantageous to employ a much cheaper type of flue system for conveying the products of combustion therethrough, and which will at the same time increase the radiation of heat from the spent gases and assist in extracting as much heat as possible therefrom, before they are discharged.

To this end I have shown in Fig. 4 a system of metal pipes or conduits, indicated at 40, arranged upon the platform, 9, at each side of the kiln, which pipes or conduits are in connection at their inner ends with the flues, 30, and transmit the products of combustion therefrom to a discharge pipe or pipes, indicated at 50, see Fig. 1, by which they may be conducted to a suitable exhaust fan or stack (not shown) wherein a draught is created so that there will be a suction from the pipe 50 through the heating flues, 40 and 30, and receiving flues, 12, which suction will draw the products of combustion into the receiving flues, 12, through the ori- 115 fices, 21, before described. In order to prevent direct radiation of heat from the pipes, 40, to the lateral portions of the piles of brick or other goods, which might result in 120 an unequal heating of the same, and lead to 125 130

premature firing of the outer rows of the pile in the firing kiln, and consequent outward toppling of the bricks or unequal firing of the same, I provide a screen or wall 5 of brick or other suitable material, indicated at 41, between the pipes, 40, and the central goods space to prevent this direct radiation and insure the delivery of the heated air passing around the pipes to the upper 10 central portion of the kiln. This screen wall is preferably provided with openings, 42, at its lower portion, at about the upper surface of the platform, 9, through which the air from the central goods space of the kiln may readily enter and circulate upwardly 15 over the heating pipes, 40. It will be understood that Fig. 4, as well as Fig. 3, are partial sections showing only one side of the kiln structure at the points where the sections are taken and that the opposite side, not shown at each of the sections, is constructed correspondingly.

Suitable means are provided for introducing atmospheric air into the front end 20 of the preheating section of the kiln, and the air within the preheating section, B, coming in contact with the flues, 40 and 30, is gradually heated as it passes rearwardly, and is caused to circulate upwardly at the 25 sides of the kiln, to the top of the kiln and thence downwardly and laterally through the piles of goods on the cars. I have indicated diagrammatically, a fan 60 at the rear end of the preheating section, B, of the kiln, 30 for drawing the air longitudinally therethrough and discharging it therefrom. In order that the heat remaining in the air may be utilized to the greatest advantage, this heated air withdrawn from the preheating chamber will be advantageously fed 35 to the furnaces to assist in the combustion of the fuel therein, and I have indicated diagrammatically, a pipe, 61, connected with the fan, 60, provided with branch pipes, 62, to the various furnaces, and this distribution of the air may be effected in any convenient or desired manner, according 40 to the character of the fuel employed. I may use two fans, 60, as indicated in Fig. 1, or I may use one or more as may be required to accomplish the desired result.

C represents a cooling section of the kiln extending rearwardly from the firing section, A. This portion of the kiln is not required to be constructed in the same manner as those in which heat is to be imparted to the goods as it is the function of this portion of the kiln to gradually cool the goods by permitting and facilitating radiation of heat therefrom. Accordingly, I prefer to form the walls of this section so as to outline the space occupied by the goods and their conveying trucks or cars in a well known way and these walls may be made of brick or metal, or both, or partly of brick 55 and partly of metal, as may be desired to carry out this action. The cooling section, C, is also provided with the usual cooling flue or flues, extending longitudinally therethrough, for the purpose of drawing in cool 70 air and facilitating the withdrawal of heat from the goods and the walls of the cooling section. This portion of the kiln follows usual kiln practice, and I have not specifically illustrated the sectional construction 75 of the cooling system of the same, as the specific construction thereof has no bearing on my present invention. The cooling section of the kiln is provided with a fan or fans, indicated at 70, for promoting a circulating of air into and through the cooling section, the air being discharged by the fan or fans, 70, through pipes, 71, by which it is preferably conveyed through a drying chamber wherein the green clay products 80 are dried, preliminary to passing to the kiln, in order that the heat radiated by the goods 85 in cooling, may be advantageously utilized.

In the drawings, 80—80, represent supporting rails or tracks, extending longitudinally through the entire length of the tunnel kiln. 90, represents trucks or cars, which are preferably provided with metallic frames, indicated at 91, and provided with wheels, 92, running on the tracks, 80, 95 each truck being provided with a superstructure, indicated at 93, 94 and 95, of fire resisting material such as fire brick or the like, and one or more sections of the superstructure extends laterally beyond the overhanging ledges 11 of the lateral platform, 100 so as to exclude the heat from the truck frame and wheels as far as possible. I also prefer to provide the space between the platforms with auxiliary cooling means, such as a series of pipes, 96, on each side of the said space, for example, through which cool air can be passed for the purpose of maintaining a comparatively low temperature 105 adjacent to the truck frames and wheels. The uppermost layer, 95, of the truck superstructure is preferably formed in two parts, slightly separated at the longitudinal center of the truck, and provided with horizontal passage, indicated by dotted lines, at 110 97, the upper faces of the sections, 95, being respectively inclined downwardly toward the longitudinal center of the truck, and the bricks or other goods piled thereon in the usual manner will, therefore, be in the form of two laterally arranged piles inclining 115 slightly toward each other but leaving a central longitudinal passage between them for the downward passage of the products of combustion in the firing zone of the kiln and for the heated air in the preheating section, and for the cooling air in the cooling section. It will be understood that the cars 120 will be introduced one at a time at the forward end of the kiln, and moved gradually 125

- toward the rear until the entire kiln from one end to the other is filled with cars, after which, at suitable intervals, a car is introduced at the front end of the kiln by suitable car moving apparatus, not shown, thereby pushing the remaining cars to the rear and discharging the last car from the cooling section, so that the operation of the kiln is continuous.
- 10 Any desired type of fuel can be used in the furnaces, 7, according to the location of the plant or the cheapness and plentifulness of fuel at such location. The fuel may be coal, wood, gas or oil, as may be found most economical and desirable. As the combustion occurs in the furnaces and the products of combustion are discharged directly into the firing section of the kiln in contact with the goods to be fired, which 20 are of such a character as not to be injured thereby, the greatest possible economy in the firing of goods of this character is effected without the necessity of costly construction and with a minimum of wear and tear and expense of upkeep, while the products of combustion are taken into the receiving flues and carried thereby into the heating flues extending through the preheating section or sections of the kiln so as to utilize the heat 30 of the spent gases in the most efficient and economical manner, thus securing a very high efficiency in the utilization of heat, with greatly reduced cost of construction, operation and upkeep, and insuring a maximum of continuous output. My improved kiln also possesses the distinct advantage that it may be erected anywhere where any sort of fuel is available at reasonable prices without imposing upon the operator the necessity of using a particular kind of fuel, as gas, and the expense and care of constructing and operating a producer gas plant in addition to the kiln.
- 40 What I claim and desire to secure by Letters Patent is:—
1. In a tunnel oven, the combination with a firing chamber having a goods space extending longitudinally thereof, direct firing furnaces for said chamber, said chamber being provided with discharge passages for said furnaces communicating with said chamber near the top thereof, and means for deflecting the products of combustion downward centrally of the goods space, receiving flues located on opposite sides of said chamber, and interposing an imperforate wall between the said passages and the goods space, said receiving flues being provided with inlet ports on their inner faces adjacent to the lower portion of the goods space, and means for preventing the products of combustion discharged from said discharge passage into said chamber from passing downwardly therefrom between the goods and the inner walls of the receiving flues.
- 50 2. In a tunnel oven, the combination with a firing chamber having a goods space extending longitudinally thereof, direct firing furnaces for said chamber, said chamber being provided with discharge passages 70 for said furnaces communicating with said chamber near the top thereof, and means for deflecting the products of combustion downward centrally of the goods space, receiving flues located on opposite sides of said chamber, and interposing an imperforate wall between the said passages and the goods space, said receiving flues being provided with inlet ports on their inner faces adjacent to the lower portion of the goods space, and longitudinally disposed guard flanges extending from the upper ends of the inner walls of said receiving flues and projecting upwardly and inwardly toward the goods space, to prevent the products of combustion from 80 said discharge flues passing downwardly therefrom between the goods and the inner walls of the receiving flues.
3. In a tunnel oven, the combination with a firing chamber having a goods space extending longitudinally thereof, direct firing furnaces for said chamber, said chamber being provided with discharge passages for said furnaces communicating with said chamber near the top thereof, and means for deflecting the products of combustion downward centrally of the goods space, receiving flues located on opposite sides of said chamber, and interposing an imperforate wall between the said passages and the goods space, said receiving flues being provided with inlet ports on their inner faces adjacent to the lower portion of the goods space, and longitudinally and horizontally disposed ribs on the inner walls of said receiving flues, extending toward the goods space, to prevent the products of combustion from said discharge flues passing downwardly therefrom between the goods and the inner walls of said receiving flues.
4. In a tunnel oven, the combination with a firing chamber having a goods space extending longitudinally thereof, direct firing furnaces for said chamber, said chamber being provided with discharge passages for said furnaces communicating with said chamber near the top thereof, and means for deflecting the products of combustion downward centrally of the goods space, receiving flues located on opposite sides of said chamber, and interposing an imperforate wall between the said passages and the goods space, said receiving flues being provided with inlet ports on their inner faces adjacent to the lower portion of the goods space, and longitudinally and horizontally disposed ribs on the inner walls of said receiving flues located in different horizontal planes and extending toward the goods space to prevent the products of combustion from said dis-

charge flues passing downwardly therefrom between the goods and the inner walls of said receiving flues.

5. In a tunnel oven, the combination with a firing chamber having a goods space extending longitudinally thereof, direct firing furnaces for said chamber, said chamber being provided with discharge passages for said furnaces communicating with said chamber near the top thereof, and means for deflecting the products of combustion downward centrally of the goods space, receiving flues located on opposite sides of said chamber and interposing an imperforate wall between the said passages and the goods space, said receiving flues being provided with inlet ports on their inner faces adjacent to the lower portion of the goods space, and longitudinally and horizontally disposed ribs on the inner wall of said receiving flues located in different horizontal planes and extending toward the goods space, said ribs varying in horizontal width and decreasing in width from the bottom of said flues upwardly, to prevent the products of combustion from said discharge flues passing downwardly therefrom between the goods and the inner walls of said receiving flues.

6. In a tunnel oven, the combination with a firing chamber having a goods space extending longitudinally thereof, direct firing furnaces for said chamber, said chamber being provided with discharge passages for said furnaces communicating with said chamber near the top thereof, and means for deflecting the products of combustion downward centrally of the goods space, receiving flues located on opposite sides of said chamber and interposing an imperforate wall between the said passages and the goods space, said receiving flues being provided with inlet ports on their inner faces adjacent to the lower portion of the goods space, longitudinally disposed guard flanges extending from the upper ends of the inner walls to said receiving flues and projecting upwardly and inwardly therefrom, and longitudinally and horizontally disposed ribs on the inner walls of said receiving flues below said guard flanges, to prevent the products of combustion from said discharge flues passing downwardly therefrom between the goods and the inner walls of the receiving flues.

7. In a tunnel oven, the combination with a firing chamber having a goods space extending longitudinally thereof, direct firing furnaces for said chamber, said chamber being provided with discharge passages for said furnaces communicating with said chamber near the top thereof, and means for deflecting the products of combustion downward centrally of the goods space, receiving flues located on opposite sides of said chamber and interposing an imperforate wall between the said passages and the goods space, said re-

ceiving flues being provided with inlet ports on their inner faces adjacent to the lower portion of the goods space, longitudinally disposed guard flanges extending from the upper ends of the inner walls to said receiving flues and projecting upwardly and inwardly therefrom, and longitudinally and horizontally disposed ribs on the inner walls of said receiving flues below said guard flanges, said ribs being located in different horizontal planes and extending toward the goods space.

8. In a tunnel oven, the combination with a firing chamber having a goods space extending longitudinally thereof, direct firing furnaces for said chamber, said chamber being provided with discharge passages for said furnaces communicating with said chamber near the top thereof, and means for deflecting the products of combustion downward centrally of the goods space, receiving flues located on opposite sides of said chamber and interposing an imperforate wall between the said passages and the goods space, said receiving flues being provided with inlet ports on their inner faces adjacent to the lower portion of the goods space, longitudinally disposed guard flanges extending from the upper ends of the inner walls to said receiving flues and projecting upwardly and inwardly therefrom, and longitudinally and horizontally disposed ribs on the inner walls of said receiving flues below said guard flanges, said ribs being located in different horizontal planes and varying in horizontal width, said ribs decreasing in width from the bottom of the flues upwardly.

9. In a tunnel oven, the combination with a firing chamber, having a goods space extending longitudinally thereof, direct firing furnaces for said chamber located laterally with respect to said goods space and provided with discharge passages communicating with the chamber adjacent to the top thereof, said chamber being provided with a curved roof having a downwardly extending longitudinal deflector located centrally above the goods space, receiving flues located on opposite sides of the goods space, and interposing an imperforate wall between said passages and the goods space, and provided with inlet ports on their inner faces, said receiving flues being provided at their upper edges with longitudinal guard flanges extending upwardly, and inwardly beyond the vertical plane of the inner wall of the flue, and having their outer faces curved substantially in conformity with the curved roof, the spaces between said flanges and the roof forming portions of said discharge passages.

10. In a tunnel oven, the combination with a firing chamber, having a goods space extending longitudinally thereof, direct fir-

ing furnaces for said chamber located laterally with respect to said goods space and provided with discharge passages communicating with the chamber adjacent to the top thereof, said chamber being provided with a curved roof having a downwardly extending longitudinal deflector located centrally above the goods space, receiving flues located on opposite sides of the goods space, and interposing an imperforate wall between said passages and the goods space, and provided with inlet ports on their inner faces, and means for preventing down draught from said discharge passages between the goods in the goods space and the inner walls of said receiving flues.

11. In a tunnel oven, the combination with a firing chamber, having a goods space extending longitudinally thereof, direct firing furnaces for said chamber located laterally with respect to said goods space and provided with discharge passages communicating with the chamber adjacent to the top thereof, said chamber being provided with a curved roof having a downwardly extending longitudinal reflector located centrally above the goods space, receiving flues located on opposite sides of the goods space, and interposing an imperforate wall between said passages and the goods space, and provided with inlet ports on their inner faces, the inner walls of said receiving flues being provided with inwardly projecting horizontally disposed longitudinal ribs, for preventing down draught from the discharge passages between the goods and said inner walls.

12. In a tunnel oven, the combination with a firing chamber, having a goods space extending longitudinally thereof, direct firing furnaces for said chamber located laterally with respect to said goods space and provided with discharge passages communicating with the chamber adjacent to the top thereof, said chamber being provided with a curved roof having a downwardly extending longitudinal deflector located centrally above the goods space, receiving flues located on opposite sides of the goods space, and interposing an imperforate wall between said passages and the goods space, and provided with inlet ports on their inner faces, the inner walls of said receiving flues being provided with inwardly projecting horizontally disposed longitudinal ribs, the upper portions of said receiving flues being provided with longitudinal guard flanges extending upwardly, and inwardly beyond the inner walls of said flues to prevent down draught from the discharge passages between the said flues and the goods.

13. A tunnel oven having a longitudinally disposed chamber comprising a firing zone, and zones of lower temperature, direct firing furnaces for the firing zone provided

with discharge passages for discharging the products of combustion toward the top of the chamber and deflecting them downward centrally upon the goods, receiving flues in the firing zone disposed on opposite sides of the goods space, and interposing imperforate walls between said discharge passages and the goods, said flues being provided with inlet ports on their inner faces adjacent to the bottom of the goods space, means for preventing the downward passage of the products of combustion in the firing zone from the discharge passages into the space between the inner walls of the receiving flues and the goods, and heating flues independent of the oven structure extending longitudinally through a lower temperature zone of the oven and communicating with the receiving flues.

14. A tunnel oven having a longitudinally disposed chamber comprising a firing zone, and zones of lower temperature, direct firing furnaces for the firing zone provided with discharge passages for discharging the products of combustion toward the top of the chamber and deflecting them downward centrally upon the goods, receiving flues in the firing zone disposed on opposite sides of the goods space, and interposing imperforate walls between said discharge passages and the goods, said flues being provided with inlet ports on their inner faces adjacent to the bottom of the goods space, means for preventing the downward passage of the products of combustion in the firing zone from the discharge passages into the space between the inner walls of the receiving flues and the goods, and heating flues independent of the oven structure extending longitudinally through a lower temperature zone of the oven and communicating with the receiving flues, means for effecting a circulation of air from the cooler end of said lower temperature zone in a direction toward the firing zone, and means for conducting the heated air and delivering it to the direct firing furnaces.

15. In a tunnel oven having a longitudinally disposed chamber, comprising a firing zone, and a preheating zone of lower temperature, direct firing furnaces for the firing zone provided with discharge passages for delivering the products of combustion adjacent to the top of the chamber and deflecting them downward centrally upon the goods, receiving flues in the firing zone located within the oven on opposite sides of a central goods space, the walls of said receiving flues being constructed of fire brick, and said flues being provided with inlet ports on their inner faces adjacent to the bottom of the goods space, the preheating zone of the oven being provided with heating flues for the air within said chamber arranged on opposite sides of the central

- goods space and connected with said receiving flues at one end so as to receive the products of combustion of said furnaces after they have parted with a considerable portion of their heat within the firing zone.
16. In a tunnel oven provided with a firing zone and a preheating zone, direct firing furnaces for the firing zone, and means for discharging the products of combustion therefrom directly into the interior of the firing zone in contact with the goods, indirect heating means within the preheating zone for heating the air therein, and means for conducting the products of combustion from the firing zone through the indirect heating means within the preheating zone out of contact with the goods in the preheating zone.
17. In a tunnel oven provided with a firing zone and a preheating zone, direct firing furnaces for the firing zone, and means for discharging the products of combustion therefrom directly into the interior of the firing zone in contact with the goods, indirect heating means within the preheating zone for heating the air therein, means for conducting the products of combustion from the firing zone through the indirect heating means within the preheating zone out of contact with the goods in the preheating zone, and means in the preheating zone for preventing the direct radiation of heat from the indirect heating means to the goods.
18. In a tunnel oven having a longitudinally disposed chamber, comprising a firing zone and preheating zones of lower temperature, direct firing furnaces for the firing zone provided with discharge passages for delivering the products of combustion directly into the top of said chamber and deflecting them downward centrally upon the goods, indirect heating flues located within the preheating zone adjacent to the firing zone and connected therewith so as to receive the products of combustion after they have parted with a considerable portion of their heat, for heating the air in said preheating zone, and indirect heating flues having greater radiating properties than the first mentioned heating flues extending through another preheating zone further removed from the firing zone, and adapted to receive the further cooled products of combustion from the first mentioned heating flues, and means for creating a circulation of the products of combustion from the firing zone successively through the heating flues within the said preheating zones of the oven.
19. In a tunnel oven having a longitudinally disposed chamber comprising a firing zone and preheating zones of lower temperature, direct firing furnaces for the firing zone provided with discharge passages for discharging the products of combustion into
- said chamber adjacent to the top thereof, and deflecting them downward centrally upon the goods, receiving flues of fire brick within the firing zone, on opposite sides of the goods space, said flues having inlet ports 70 on their inner faces adjacent to the bottom of the goods space, indirect air heating flues within the preheating zone adjacent to the firing zone located on opposite sides of the goods space and formed of tiling and communicating with the receiving flues, indirect heating flues of metal located within another preheating zone further removed from the firing zone, flues communicating with the flues of the preceding preheating zone, and fire resisting walls on opposite sides of the goods space in both of said preheating zones between the goods space and the adjacent heating flues to prevent direct radiation to the goods.
20. In a tunnel oven, walls defining a firing chamber extending longitudinally of the oven, means for conducting goods through said chamber, direct firing furnaces and means for discharging the products of combustion from said furnaces into said firing chamber, said goods when conducted through said firing chamber being closely positioned with respect to said walls, together with means arranged in the space between said walls and the goods being conducted through said chamber for preventing down draft along the lateral sides of the goods being conducted through the chamber.
21. In a tunnel oven, walls defining a firing chamber extending longitudinally of the oven, means for conducting goods through said chamber, direct firing furnaces and means for directing the products of combustion therefrom into said chamber, together with means associated with said walls for preventing down draft between the walls and the lateral sides of the goods.
22. In a tunnel oven, walls defining a firing chamber extending longitudinally of said oven, means for conducting goods through said chamber, direct firing furnaces and means for discharging the products of combustion therefrom into said chamber, together with longitudinal laterally extending baffles carried by the walls for preventing down draft between said walls and the lateral sides of the goods.
23. In a tunnel oven, walls defining a firing chamber extending longitudinally of said oven, means for conducting goods through said oven, direct firing furnaces and means for discharging the products of combustion therefrom into the upper portion of said chamber, together with longitudinally extending baffles projecting laterally from said walls to prevent down draft between said walls and the lateral sides of the goods, said baffles being of different horizontal widths.

24. In a tunnel oven, walls defining a firing chamber extending longitudinally of said oven, means for conducting goods through said oven, direct firing furnaces and means for discharging the products of combustion therefrom into the upper portion of said chamber, together with a series of longitudinally extending baffles projecting later-

ally from said walls to prevent down draft between said walls and the lateral sides of the goods, said baffles gradually decreasing in horizontal width from the lowest to the highest one of the series.

In testimony whereof I affix my signature.

WILLIAM LEE HANLEY, JR.
